UNITED STATES PATENT OFFICE.

PLINY N. JOSLIN, OF DE KALB, ILLINOIS.

HOTEL-ROOM-RECORD RACK.

Application filed September 10, 1923. Serial No. 661,881.

The invention is concerned with rack structures such as are suitable for employment in the maintenance of record systems wherein data pertaining to co-related matters may be consolidated for the purpose of ready reference.

The invention has for its principal purpose the provision of a novel record rack which, when employed for instance in a hotel office for use in conjunction with a list of hotel rooms, may be indicated of such temporarily pertinent information as the dates of future reservations for particular rooms, the identities of the occupants of the rented rooms, the presence or absence of baggage in the rented rooms, the condition of the vacated rooms, and the like. While its adaptation as a hotel room record rack probably exercises to best advantage the extensive utility of the invention, the record rack is, of course, susceptible of other diversified uses equally within the purview of the invention.

Other objects and advantages of the invention will become evident upon a full understanding of the same as set forth in the following description and accompanying drawings, wherein is presented for the purpose of exemplification what is now considered to be a preferred structural embodiment of the invention. Obviously the invention may be embodied in other modified forms without affecting the underlying principle of the same; wherefore the particular embodiment presented in this disclosure is not to be considered as limiting the spirit of the invention or as restricting unnecessarily the scope of the claims.

In the drawings,

Fig. 1 is a front view of one corner of a rack constructed in accordance with the invention;

Fig. 2 is a horizontal section on the line 2—2 of Fig. 1;

Fig. 3 is a vertical section on the line 3—3 of Fig. 2;

Fig. 4 is a vertical section on the line 4—4 of Fig. 2;

Fig. 5 is a perspective detail view of the slide in one indicating device;

Fig. 6 is a perspective detail view of the slide in the other indicating device;

Fig. 7 is a front view of a card adapted for use in the upper pocket of each group;

Fig. 8 is a front view of a card adapted for use in the lower pocket of each group;

Fig. 9 is a front view of one corner of the rack, illustrating a modified form;

Fig. 10 is a horizontal section on the line 10—10 of Fig. 9;

Fig. 11 is a front view of one corner of the rack, illustrating another modified form; and

Fig. 12 is a front view of a card adapted for use in the single pocket construction illustrated in Fig. 11.

It will be observed, in Figs. 1 to 8 inclusive of the drawings, that the rack of the invention is characterized by a support 10 to which a plurality of horizontally elongated members 11 are attached in one or more vertical columns.

The support 10 has a backing portion 12 which provides tongues 13 for co-action with slots 14 in the members adjacent the sides thereof, and a frame-work 15 which provides both inwardly turned flanges 16 for positioning the members against the attaching projections in one or more vertical columns and surfaces 17 to the left side of the members for presenting a permanent list of identifying symbols 18 alongside groups of the members.

Each of the groups referred to includes a lower member 19, an intermediate member 20, and an upper member 21. An upwardly opening pocket 22 is formed between the members 19 and 20 for the reception of the lower portion only of a removable card 23; another upwardly opening pocket 24 is formed between the members 20 and 21 for the reception of the lower portion only of a card 25 which has an upper portion of less width than the card 23 for which the pocket 22 is adapted; and two indicating devices 26 and 27 associated with the member 21. The indicating devices are arranged in spaced relation at locations just above the margin of the exposed upper portion of the card 23 when in the pocket 22 and on opposite sides of the margin of the exposed upper portion 100 of the card 25 when in the pocket 24.

The indicating devices are substantially

similar to each other, and each consists of an aperture 28 in a horizontally grooved exposed portion of the member 21, a slide 29 movable in spaced guides provided by the 5 groove in the member, and a tab 30 which extends upwardly from the slide through a slot in the groove of the member and provides a means for shifting the slide horizontally of the member whereby to expose 10 through the aperture 28 differently colored portions 31 or 32 of the slide.

The rack of the invention may be employed as a hotel room record in the following manner:

15 The identifying symbols 18 may represent the numbers of the hotel rooms; the cards 23 may be placed in certain of the lower pockets 22, and may have inscribed on their upper exposed portions the names of the occupants 20 renting those rooms and on their lower hidden portions any confidential information which it is desirable to have in the record; the cards 25 may be placed in certain of the upper pockets 24 with their reduced upper 25 portions disposed between the indicating devices 26 and 27, and may have inscribed on their exposed upper portions notations regarding future reservations for those particular rooms; the indicating devices 26 may 30 be shifted to one side to expose through the aperture a portion indicating the presence of baggage in those rooms, or may be shifted to expose a portion indicating the absence of baggage in those rooms; and the indicating devices 27 may be shifted to one side to expose 35 through the aperture a portion indicating that those rooms are not in a condition for re-renting, or may be shifted to expose a portion indicating that those rooms are in 40 condition for re-renting.

When applying the arbitrary meanings above given the foregoing symbols, it will be understood that room No. 101, for instance, has not been reserved, has no present 45 occupant, and is in a condition for re-renting; that room 103, for instance, has been reserved for June 4th but is at present in a condition for re-renting; and that room 104, for instance, is now being occupied by John 50 Smith, who has baggage in the room.

By the employment of a rack of this character, the pertinent information relating to the hotel rooms may be temporarily consolidated in a compact form for ready reference. 55 The advantages of such a record rack are numerous for it will be appreciated that, by reference to the rack, any pertinent information concerning the rooms may be readily had. When the rack is used as a record for 60 hotel rooms, it will of course be understood that the information concerning the presence or absence of baggage in the rooms and the condition of the rooms will be telephoned by the caretakers of the rooms to the office 65 where the rack is installed.

In Figs. 9 and 10 is illustrated a modified form of the rack wherein the lower member 19 of the first form is omitted in each group of horizontally elongated members 11 and the pocket 33 presented behind the upper member 21 of each group is used as the lower pocket 22 of the above group, whereby a more compact arrangement of the numerous groups is produced.

In Fig. 11 is illustrated another still further modified form of the rack wherein the lower member 19 and the intermediate member 20 of the first form are both omitted in each group. In this form of the invention only one pocket 34 is produced in association with the two indicating devices 27 and the devices are accordingly set further apart to accommodate therebetween the wider exposed portion of a name and data card 35.

What I claim is:

1. In a record rack, an upwardly opening pocket for the reception of the lower portion of a card, and a changeable indicating device associated with the rack for the optional display of a symbol at a point so located with respect to the pocket and the size of card used as to be adjacent the exposed upper portion of a card when in the pocket, said indicating device including a member having an aperture therein, a slide carried by the member at the rear thereof and having a portion visible through the aperture, and means accessible from in front of the member for shifting the slide relative to the aperture.

2. In a record rack, two upwardly opening pockets arranged one above the other and adapted to receive in the lower pocket a card having a relatively wide upper exposed portion and in the upper pocket a card having a relatively narrow upper exposed portion, and a changeable indicating device mounted within a portion of the rack above both pockets at a location which is directly opposite one side of the exposed portion of the upper card and directly above one end of the exposed portion of the lower card.

3. In a record rack, two upwardly opening pockets arranged one above the other and adapted to receive in the lower pocket a card having a relatively wide upper exposed portion and in the upper pocket a card having a relatively narrow upper exposed portion, and two changeable indicating devices mounted within a portion of the rack above both pockets at locations which are directly opposite the sides of the exposed portion of the upper card and directly above the ends of the exposed portion of the lower card.

4. In a record rack, a support, a plurality of horizontally elongated members assembled with the support in overlapping relation to each other to form between two of said members an upwardly opening pocket for holding a card with the upper exposed por-

tion thereof in front of the otherwise exposed portion of the upper one of said members, an aperture in the upper one of said members at a location above the pocket which is 5 at one side of the exposed portion of a card when in the pocket, an indicating slide mounted behind the aperture in movable re-

lation thereto, and means accessible from in front of the apertured member for moving 10 the slide whereby to expose through the aperture different portions of the same.

In testimony whereof I have hereunto signed my name.

PLINY N. JOSLIN.
